US0D1107657S

(12) **United States Design Patent** (10) **Patent No.:** **US D1,107,657 S**
(45) **Date of Patent:** **** Dec. 30, 2025**

(54) **HERMETIC TERMINAL**

- (71) Applicant: **SCHOTT Japan Corporation**, Koka (JP)
- (72) Inventors: **Daisuke Fukushima**, Koka (JP); **Hiroki Honda**, Koka (JP); **Akira Fujioka**, Koka (JP); **Yohei Otani**, Koka (JP)
- (73) Assignee: **SCHOTT JAPAN CORPORATION**, Shiga (JP)
- (**) Term: **15 Years**

(21) Appl. No.: **29/920,555**

(22) Filed: **Dec. 12, 2023**

Related U.S. Application Data

- (62) Division of application No. 29/813,232, filed on Oct. 27, 2021, now Pat. No. Des. 1,060,265.

(57) **CLAIM**

The ornamental design for a hermetic terminal, as shown and described.

DESCRIPTION

FIG. 1 is a front view of a hermetic terminal showing our new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a cross-sectional view taken along line 7-7 of FIG. 5;

FIG. 8 is an upper perspective view thereof; and,

FIG. 9 is a lower perspective view thereof.

The broken lines in the figures illustrate the portions of the hermetic terminal that form no part of the claimed design.

1 Claim, 5 Drawing Sheets
